TOBACCO PIPE

Raymond F. Hallstein, Philadelphia, Pa.

Application December 11, 1936, Serial No. 115,432

4 Claims. (Cl. 131—12)

This invention relates to tobacco pipes, and its general object is to provide a pipe in which the smoke passages can be retained free from obstructions, with minimum effort on the part 5 of the user, merely by movement or rotation of the mouth piece, which when rotated in one direction will remove any obstructions that clog the passage of the stem at its juncture with the bore of the bowl, and when rotated in an opposite direction will dispose the mouth piece in binding fitting association with the stem regardless of any change in the diameter of the mouth piece receiving bore thereof, caused by expansion or contraction, with the result the mouth 10 piece does not have to be removed from the stem for cleaning purposes and is held fixed against casual removal or displacement when in use.

Another object is to provide a tobacco pipe that includes a hollow stem which not only provides a chamber for housing the parts for cleaning the smoke passage thereof, and fixing the mouth piece thereto, but also provides a liquid trap to prevent saliva or the like from draining into the bowl or filling the smoke passage of the 15 mouth piece.

A further object is to provide a pipe of the character set forth, that is simple in construction, inexpensive to manufacture, and extremely efficient in use, operation and service.

30 This invention also consists in certain other features of construction and in the combination and arrangement of the several parts, to be hereinafter fully described, illustrated in the accompanying drawing and specifically pointed out in the appended claims.

35 In describing the invention in detail, reference will be had to the accompanying drawing wherein like characters denote like or corresponding parts throughout the several views, and in which: 40 Figure 1 is a side elevation of the pipe which forms the subject matter of the present invention, with parts in section.

Figure 2 is a top plan view of the mouth piece 45 of my pipe and which has secured thereto the working parts of the invention.

Figure 3 is a sectional view taken approximately on line 3—3 of Figure 2, looking in the direction of the arrows.

50 Figure 4 is a sectional view taken approximately on line 4—4 of Figure 1, looking in the direction of the arrows.

Figure 5 is a perspective view of the guide and binding disk collar.

55 Figure 6 is a view illustrating the bowl and

stem of my pipe in section, to show one of the guide grooves.

Figure 7 is a longitudinal sectional view taken through the mouth piece and the tube that is fixed thereto.

Referring to the drawing in detail, the reference numeral 1 indicates the bowl of my pipe having the usual tobacco receiving bore 2 therein, and formed with the bowl is a stem 3 which is hollow to provide a chamber 4, the latter communicating with the bore 2 through the medium of a passage 5.

The mouth piece which is indicated by the reference numeral 6 is provided with a flattened outer end, in the form as shown, and formed on the opposite end is a reduced extension 7 providing a shoulder and receivable in the chamber of the stem for frictional association with the wall thereof, as will be apparent upon inspection of Figure 1.

The mouth piece is provided with the usual smoke passage 8, and mounted in the extension to project within the mouth piece, is a tube 9 which has its inner end outwardly flared as at 10, and embedded within the mouth piece for 15 fixedly securing the tube thereto, as will be apparent. The bore of the tube is aligned with and communicates with the smoke passage 8, and the tube projects a considerable distance beyond the outer end of the extension 7, as best 20 shown in Figure 7, the projecting portion being screw threaded as at 11, and formed on the outer end of the tube is a stop flange 12 for a purpose 25 which will be later described.

30 Threadedly mounted on the portion 11 of the tube 9 is the collared portion 13 of a travelling member 14 which is shown as being hollow as at 35 15 for the purpose of receiving the stop flange 12, and the forward end is rounded to provide 40 a nose 16 which has secured thereto by being preferably threaded therein, a pin 17 that extends forwardly from the nose to be received in the passage 5, as clearly shown in Figure 1. The upper portion of the travelling member is 45 open, and arranged in the sides thereof are openings 18 providing outlet means for liquid.

Formed on and extending from diametrically opposite sides of the collared portion 13 are lugs 19 which are mounted in diametrically opposed 50 grooves 20 that extend longitudinally in the sides of the chamber 4, as best shown in Figure 6, therefore it will be apparent that the travelling member is held against rotation for movement longitudinally in the chamber for disposing the 55

pin 17 into and out of the passage 5 for cleaning the same of obstructions.

Mounted on the unthreaded portion of the tube 9 is a collar 21 having a disk flange 22 formed on one end thereof, and the flange 22 is provided with lugs 23 which are mounted in the grooves 20. The free end of the extension 1 is convexed as best shown in Figure 3 and disposed between the convexed free end and the disk flange 22 is a split washer 24, the latter having a concaved face to fit the free end and a flat outer face for receiving the disk flange, and the washer is formed from flexible material so as to readily expand or contract for securing and releasing the mouth piece with respect to the stem. Disposed between the disk flange 22 and the collared portion 13 is a coil spring 25 which is forced against the flange 22 upon rearward movement of the travelling member for expanding the washer in binding engagement with the wall of the chamber.

From the above description and disclosure of the drawing, it will be obvious that upon rotation of the mouth piece in one direction it will cause the member 14 to travel forwardly on the tube 9, thereby removing obstructions from the passage 5, and upon rotation of the mouth piece in an opposite direction the member 14 will travel inwardly on the tube and against the coil spring 25 which moves the flange 22 against the washer 24, thereby causing the washer to expand into binding engagement with the chamber for fixedly associating the mouth piece with respect to the stem as will be apparent.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A tobacco pipe comprising a bowl, a stem 45 for the bowl having a passage communicating with the bore thereof, a mouth piece received in the stem, movable means on the mouth piece, means carried by the movable means and movable through the passage to remove obstructions 50 therefrom upon rotation of the mouth piece in one direction, expandible and contractable means on the mouth piece and acted upon by the movable means to be expanded in binding engagement with the stem upon rotation of the mouth

piece in an opposite direction for securing the latter to the stem.

2. A tobacco pipe comprising a bowl, a stem for the bowl and having a passage communicating with the bore thereof, a mouth piece frictionally mounted in the stem, a tube extending from the mouth piece and received in the stem, a travelling member threaded to the tube for movement longitudinally thereon, means to prevent rotation of the travelling member, and means extending from the travelling member for movement through the passage to remove obstructions therefrom upon rotation of the mouth piece.

3. A tobacco pipe comprising a bowl, a stem 15 for the bowl and having a passage communicating with the bore thereof, a mouth piece received in the stem, a tube extending from the mouth piece, a hollow travelling member including a collar threaded on the tube for movement longitudinally thereof, means to prevent rotation of the travelling member, a pin extending from the outer end of the travelling member and received in the passage to remove obstructions therefrom upon rotation of the mouth piece in one direction, expandible and contractable means on the tube, and means engageable therewith for expanding the same in binding engagement with the stem and acted upon by the travelling member, upon rotation of the mouth piece in an opposite direction.

4. A tobacco pipe comprising a bowl, a chambered stem for the bowl and having a passage communicating with the bore thereof, a mouth piece including an extension frictionally mounted 35 in the stem, a tube secured to the mouth piece and projecting through and beyond the extension, a travelling member threaded on the tube for movement in the chamber of the stem, a pin secured to the travelling member and movable 40 through the passage to remove obstructions therefrom upon rotation of the mouth piece in one direction, expandible and contractable means on the tube, collared means engageable with the expandible and contractable means, and a coil 45 spring movable against the collared means by the travelling member for moving the expandible and contractable means against the extension for expanding the same into binding engagement with the stem upon rotation of the mouth piece 50 in an opposite direction for securing the latter to the stem.

RAYMOND F. HALLSTEIN.
